UNITED STATES PATENT OFFICE

JOHANN CARL ZENSES, OF REMSCHEID, GERMANY.

FILE-CUTTING MACHINE.

SPECIFICATION forming part of Letters Patent No. 600,570, dated March 15, 1898.

Application filed October 20, 1897. Serial No. 655,868. (No model.) Patented in Germany December 8, 1893, No. 85,047, and in England March 22, 1897, No. 7,395.

To all whom it may concern:

Be it known that I, JOHANN CARL ZENSES, a subject of the Emperor of Germany, residing at Remscheid, in the Province of Rhenish Prussia, Germany, have invented certain new and useful Improvements in File-Cutting Machines, (for which I have obtained patents in Germany, No. 85,047, dated December 8, 1893, comprising, however, only certain parts of the present complete application, and in Great Britain, No. 7,395, dated March 22, 1897,) of which the following is a specification.

My invention relates to an improved file-cutting machine in which the angle of the cut will always be the same and in which the pitch of the cut is made finer automatically at the pointed end, where the file itself is thinner and generally also narrower than in the middle part. At the same time my new file-cutting machine is provided with mechanisms enabling the same to cut half-round files with cuts decreasing in width toward the end of the file. I attain these objects by causing the advance of the file or of the anvil carrying the same to be executed in such a manner that tangents laid or supposed to be laid on the curve formed by the body of the file in the point of the cut shall always form the same angle with the direction or path of the chisel. For this purpose I use a templet corresponding to the shape of the file-blank and serving as a guide directing the movement of the anvil, and I cause the advance of the file to be slower at the beginning than at the middle part also by means of a templet of appropriate shape, and finally I place the half-round and similar files on a bed of such shape that the file can be bent at its end, and that in consequence of this the power of the stroke of the chisel will be uniform and equally strong at any part of the file. On the accompanying drawings the machine comprising the mechanisms for realizing these objects is shown.

Figure 1 is a side view of the complete machine, partly in section. Fig. 2 is a plan of Fig. 1. Fig. 3 is a vertical section along line I I of Fig. 1. Fig. 4 is an end view seen from the right of Fig. 1. Fig. 5 shows in detail and in an enlarged scale and in section along line II II of Fig. 7 the gear for regulating the

advance of the anvil. Fig. 6 is a side view of Fig. 5 seen from the left. Fig. 7 is a plan of Fig. 6. Fig. 8 is a plan of the bed for half-round files. Fig. 9 is a side view of Fig. 8. Figs. 10, 11, and 12 are respectively cross-sections of Fig. 8 along lines III III, IV IV, and V V. Fig. 13 is a similar section of a bed used for cutting the left part of the round face of a half-round file. Figs. 14, 15, and 16 are respectively a side view, a longitudinal section, and an end view of the worm with half a thread for advancing the anvil at intervals. Fig. 17 is a diagram showing the working of the machine.

All the working parts of the machine are carried in and erected upon a U-shaped foundation-frame A. Between the two vertical sides of this frame is guided the sliding piece B, in which is lodged the anvil W'. Upon the rear side of the frame A, at its left end, is mounted the standard A', at the front side of which is erected the hammer-guide, with the spring-box and other known parts, and which also carries the main driving-shaft C, with fast and loose pulleys C' at the rear end and the hammer-lifting cam D at the front end. The manner of guiding the hammer and of driving it down is of known design and requires, therefore, no special description. In the middle of the standard A' is keyed upon the shaft C the worm E. This worm, which has a thread that rises only half of the circumference, the other part having no inclination, gears into a worm-wheel F upon a shaft F', which is supported in double bearings G, mounted at the rear side of the foundation-frame A. The bearings G at the same time serve to carry the screw-spindle H. At the right end of the shaft F' is fixed a pulley F'', and at the corresponding end of the screw-spindle H is keyed a similar pulley H''. A guide-pulley K, fixed loosely upon a bolt K' in an adjustable bracket K'', which is secured against the corresponding standard G, serves for guiding and stretching the belt L, placed around the pulleys F'' and H''. The screw-spindle H gears into a worm-wheel M upon a shaft M', which is carried in brackets M'' upon the sliding piece B.

By means of a special arrangement, which I shall describe in detail hereinafter, the shaft

M' is allowed to turn around or to be held fast. In the latter case the worm-wheel M acts like a screw-nut, and when the spindle H is turned around the worm-wheel or nut is 5 pushed forward and with it the parts connected therewith—i. e., the shaft M', the brackets M, and the sliding piece B. Now the sliding piece B, which forms a half-circular trough, carries in this trough the anvil 10 W', as a pin or a shaft is carried in its bearing, so that the anvil can be turned or oscillated therein. This oscillation or circular movement of the anvil, while it advances with the piece B, is done in an absolutely-prescribed 15 manner and corresponding exactly with the shape or curve of the file. From it depends the maintenance of an equal angle of the cut in all parts of the file, while the chisel goes up and down always in the same direction. 20 In order to effect this, I combine with the rear or right side of the anvil a tail-bar O, passing through an opening in the rear side of the piece B and carrying at its free end a proportionate and adjustable weight O', a stilt O², 25 carrying a little roller O³ at its foot, supporting the tail-bar, and this roller O³ runs on an exchangeable templet P, which is fixed to the frame A, and the upper surface of the same is of such shape and so curved that 30 while the anvil with the sliding piece is advancing it is turned in the latter according to the shape of the templet, as will be best understood by a glance at Figs. 1 and 17. Fig. 17 shows that the angle of the direction-line a 35 of the chisel and a tangent b laid on the curve of the file-surface in any position I, II, or III is always the same, and therefore the angle of the cut made into the file is also always the same. 40 The file R is placed on an extra layer of lead on a bed Q upon the anvil. This bed is also of cylindrical form, so that it can be turned in the anvil by means of the screw S, Figs. 3 and 4, which is held in a nut S' of the 45 bracket S², screwed or riveted to the upper side of the anvil, an arm S³, linked to a nut S⁴ on the lower part of the screw S, being connected to the bed Q. 50 The file may be held down upon its bed by 55 any suitable and practical means—as, for instance, by a roller T at the end of an arm T', keyed to an axle T², carried in bearings T³, and which axle has keyed to its other end a weighted lever T⁴, which presses the roller 60 down upon the file. Besides this the file, of course, is held in place by a clamp u. These are, however, mechanisms well known and do not form part of the patent and are not my invention. 65 From the description given so far it will be understood that the anvil advances regularly and that it is turned in its trough in accordance with the curve of the file, so that the angle of the cut will always be the same 70 throughout the length of the file. Now it is not only desirable that the angle of the cut

be the same and that the pitch of the cut be the same in the main part of the file, but that the pitch gets smaller toward the pointed end, where the file is thinner and narrower, and 75 in order to realize this with my machine I provide it with the following device, (shown in detail in Figs. 5, 6, and 7:)

At the outer end of the shaft M', I place two arms U, which are connected at their lower 75 ends by a bolt u', carrying a roller U' between the arms, and in the middle by a bolt u², carrying a hand-lever U², with an eccentric U³, and upon the same shaft M', between the arms U, is keyed fast a disk V. Now it will be 80 seen from Fig. 6 that when the eccentric U³ is turned toward the disk V the arms U and the disk will be rigidly connected as if they formed one piece. In this state, therefore, when the arms U are free to turn they also 85 allow the turning of the shaft M' and of the worm-wheel M. This turning, however, is only possible when the roller U' finds no support or counteraction, whereas in the case that U' strikes or abuts against a fixture the 90 turning of the worm-wheel is stopped, and when the spindle H continues to rotate the wheel M and its connections take a linear movement. Now I place underneath the roller U'—that is, upon the frame A—a templet X 95 of a curved shape corresponding to the end of the file. Supposing, now, the arms U and the templet had the position indicated by dotted lines in Fig. 6, the roller U' rests upon the highest point of the templet, and when the 100 spindle H is turned the wheel and its connections, brackets M², and anvil B move toward the left. Hereby the roller U' loses its support upon the templet on account of the concaved shape of this. When, therefore, 105 the spindle H is turned again, the wheel M will also be turned instead of receiving a rectilinear movement until the roller U' strikes against the templet X; and now only, when the wheel M cannot be turned around any 110 farther, it is pushed forward as long as the turning of the spindle H lasts. When the roller U' has reached the straight part of the templet no more turning of the wheel M takes place and the advance of the anvil 115 will be a uniform one at every turn of the spindle H. From this it will be understood that the templet can be so shaped that the advance of the file and the anvil will be so 120 proportioned that while the narrow end is 120 under the chisel the pitch will be small at the beginning and increasing gradually until the normal part of the file is reached, when the uniform advance will begin and no more turning of the wheel will take place. By this 125 means all sorts of files of flat, triangular, or square shape can be cut in as good a manner as by hand. It is only the half-round files and those of similar shape which require still a specially-shaped support which are placed 130 upon the anvil or upon the bed Q to receive the file to be cut.

Half-round files are pointed toward the end which forms part of a cone. Now in order that this thin cone-shaped end receives a cut gradually decreasing in width and depth, I provide for such files a layer Y of the form shown by Figs. 8 to 12 for the one-half of the round face and of the symmetrical shape, as indicated by Fig. 13, for the other part of the round face. This layer is of the shape shown in section by Fig. 12 up to the line X X, the file lying with its flat face upon the surface a and bearing with its left edge against the corner b. From the point X X, where the cone part or reduced part of the file begins, the surface is made to slope and the corner b as well as the edge c converge toward each other, and the file-blank to be cut is bent to fit the surface a. By this means I can cut half-round files with a cut getting gradually narrower and less deep at the pointed half-round end than at the normal part of it. After the cutting has been finished the pile of course is made straight again.

I am aware that file-cutting machines provided with semicircularly-recessed movable sliding pieces, semicircular anvils, and means for automatically rocking the said anvils in the recesses of the said pieces have been in use before my invention, and I do not claim such a machine broadly; but

What I do claim is—

1. In a file-cutting machine, the combination with a stationary foundation-frame and a hammer and its operating mechanism mounted thereon, a sliding piece guided in said frame and having a semicylindrical recess, an anvil of semicylindrical form fitting in said recess and adapted to turn in the same under the hammer, a projecting attachment of the said anvil, fixed means acting on the said attachment to rock the said anvil as the sliding piece is moved forward, and devices for feeding the said sliding piece substantially as set forth.
2. In a file-cutting machine, in combination with a foundation-frame and a reciprocating hammer, a sliding piece having a semicylindrical recess formed therein, a semicylindrical anvil fitting in said recess and arranged to turn under the said hammer, shafts and gearing for actuating the said hammer and feeding the said slide over the frame, and means unconnected with the said shafts and gearing for automatically tilting the said an-

vil in the said recess as the slide is fed forward, substantially as set forth.

3. In a file-cutting machine in combination with a U-shaped foundation-frame A, a sliding piece B having a half-circular trough-like excavation, a half-cylindrical anvil in said excavation, a loaded tail-bar O fixed to the anvil and projecting through an opening in said piece B, a stilt O² fixed to the end of the tail-bar, a templet P, fixed to the rear part of the frame A and serving as a guide or rail for a roller O³ fixed to the foot of the stilt O², the whole as set forth and for the purpose specified.

4. In a file-cutting machine in combination with a U-shaped foundation-frame A, a sliding piece B having a half-round trough-like excavation, a half-cylindrical anvil in said excavation, a loaded tail-bar O fixed to the anvil and projecting through an opening in said piece B, a stilt O² fixed to the end of the tail-bar, a templet P fixed to the rear part of the frame A, a bracket M² secured to the top of the sliding piece B, a shaft M' journaled in said bracket and carrying two arms U and a disk V between them, said arms having a hand-lever U² and an eccentric U³ upon a bolt u² between them in the middle, and a roller U' at their outer end upon a bolt u', a templet X fixed to the upper flange of the frame A just below said roller U' the whole as set forth and for the purpose specified.

5. In a file-cutting machine, in combination with a foundation-frame and a hammer and means for actuating it mounted thereon, a sliding piece provided with a semicircular recess, a semicircular anvil mounted in said recess and adapted to be tilted therein under the said hammer, a fixed device acting on an attachment of the said anvil for automatically tilting the same as said sliding piece moves forward, means for moving the said sliding piece longitudinally, mechanism for throwing said means out of action and a fixed device arranged for contact with a roller or projecting part of the said mechanism and curved in order that such contact will automatically cause the tilting of the said anvil to be interrupted at predetermined intervals substantially as set forth.
